UNITED STATES PATENT OFFICE.

ARTHUR O. DADY, OF NEW YORK, N. Y., ASSIGNOR TO PFANSTIEHL COMPANY, INC., OF NORTH CHICAGO, ILLINOIS, A CORPORATION OF NEW YORK.

INTERNAL-COMBUSTION-ENGINE VALVE.

1,294,419.

Specification of Letters Patent. Patented Feb. 18, 1919.

Application filed January 2, 1918. Serial No. 209,894.

To all whom it may concern.

Be it known that I, ARTHUR O. DADY, a citizen of the United States, residing at New York, in the county of New York and 5 State of New York, have invented a certain new and useful Improvement in Internal-Combustion-Engine Valves, of which the following is a full, clear, concise, and exact description, reference being had to the accompanying drawing, forming a part of this specification.

This invention relates to internal combustion engine valves, and is concerned particularly with exhaust valves of the type which 15 are cooled by the application of a cooling fluid to the inner wall thereof. The objects of the invention are to provide a valve of this type having improved means for forcing the cooling fluid therethrough. A further object of the invention is to provide 20 means actuated by the movement of the valve itself for pumping the cooling fluid therethrough, and a still further object is to provide the valve with means whereby 25 the cooling fluid is taken from the water jacket surrounding the cylinder, forced through the valve and returned to the water jacket. Other objects will appear as the 30 description progresses, reference being had to the accompanying drawing, in which I have illustrated in longitudinal section a portion of a cylinder of an internal combustion engine equipped with my improved valve.

Referring to the drawing, the reference character 1 indicates the wall of a cylinder of an internal combustion engine having a bore 2 and an exhaust chamber 3 communicating therewith.

40 The reference character 4 indicates a water jacket which may be of any desired construction or configuration. The exhaust chamber 3 is provided with an exhaust port 5 having a valve seat 6 therein. An exhaust 45 valve having a hollow head 7 and a hollow stem 8 co-acts with the seat 6 to close or open the exhaust chamber. The stem of this valve slides in a sleeve bearing 9, which is secured in a suitable bore 10 in the water 50 jacket. The valve stem 8 is provided with ports 11 which are adapted to register with the ports 12 and 13 in the sleeve bearing and water jacket respectively.

The means for forcing the water through 55 the valve comprises a tube 14, which extends

into the valve stem 8 and is concentric therewith. The upper end of the tube opens into the hollow head 7 of the valve through the ports 15. The lower end of the valve stem 8 is closed by the tube 14 and the 60 flange 16, which rests upon a shoulder formed upon the tube. The lower end of the tube is enlarged at 17 as shown in the drawing, to form a pump piston which reciprocates in a cylinder 18 formed in the 65 water jacket. The lower end of this cylinder is provided with an inlet port 19 which is closed by a disk valve 20 having a stem 21, which extends through the port 19 to prevent undue displacement of the valve. A 70 cap 22, screw-threaded into the top of the cylinder head, provides means whereby the valve may be inserted or removed.

Any desired means may be employed for giving the proper movement to the exhaust 75 valve, as the details of this part of the structure form no part of my present invention. I have, however, illustrated a valve lever 23, which engages the lower side of the collar 24 to raise the valve, the collar being situated as shown, between the lower end of the valve stem and the upper end of the enlargement 17. The collar 24 is provided with a flange 25 against which the lower end of the compression spring 26 seats. The upper 85 end of the compression spring 26 abuts against the lower side portion of the water jacket.

In operation, when the valve is suddenly lifted by the lever 23 water is drawn into 90 the lower end of the tube 14 through the port 19, and when the valve is returned by the spring 26, the lower end of the tube 14 acts as a piston to force the water through the tube 14 into the hollow head and out 95 through the ports 11, 12 and 13. It will therefore be seen that I have provided means forming a part of the valve structure for producing a forced circulation of cooling fluid through the exhaust valve.

100 While I have described in detail the preferred embodiment of my invention, it is to be understood that it is capable of other adaptations and modifications within the scope of the following claims.

105 Having thus described my invention, what I claim as new and desire to secure by Letters Patent of the United States is:

1. In an internal combustion engine the combination with a cylinder having a water 110

- jacket and an exhaust port provided with a valve seat, of a tappet valve co-acting with said seat comprising a hollow head, a hollow stem communicating with said head and 5 having a port intermediate the ends thereof registering with a port in said water jacket, and pumping means for forcing water through said valve, comprising a tube arranged within said valve, one end of said 10 tube discharging into said valve head, a cylinder formed in said water jacket for receiving the other end of said tube, a port in said water jacket communicating with said cylinder, and means for reciprocating said 15 valve.
2. In an internal combustion engine the combination with a cylinder having a water jacket and a port provided with a valve seat, of a valve co-acting with said seat comprising 20 a hollow head, a hollow stem communicating with said head and having a port intermediate the ends thereof registering with a port in said water jacket, and pumping means for forcing water through said valve, 25 comprising a tube arranged within said valve, one end of said tube discharging into said valve head, a cylinder formed in said water jacket for receiving the other end of said tube, a port in said water jacket communicating with said cylinder, and means for reciprocating said 30 valve.
3. In an internal combustion engine the combination with a cylinder having a water jacket and a port provided with a valve seat, 35 of a valve co-acting with said seat comprising a hollow head, a hollow stem communicating with said head and having a port reg-

istering with a port in said water jacket, and pumping means for forcing water through 40 said valve, comprising a tube discharging into said valve, a cylinder formed in said water jacket for receiving the other end of said tube, a port in said water jacket communicating with said cylinder, and means for reciprocating said valve.

4. In an internal combustion engine the combination with a cylinder having a water jacket and a port provided with a valve seat, of a valve co-acting with said seat comprising 45 a hollow head, a hollow stem communicating with said head and having a port registering with a port in said water jacket, and pumping means for forcing water through said valve, comprising a tube discharging into said valve, a cylinder for receiving the other end of said tube, means for establishing communications between said cylinder and said water jacket, and means for reciprocating said valve.

5. In an internal combustion engine the combination with a cylinder having a valve seat, of a valve co-acting with said seat comprising a hollow stem closed at its upper 50 end and means for forcing fluid through said stem comprising one element of a pump 55 secured thereto, a second pump element co-acting with said first-named element, and means for reciprocating said valve.

In witness whereof, I hereunto subscribe my name this 21st day of December, 1917.

ARTHUR O. DADY.
